(57) **CLAIM**

The ornamental design for a faucet as shown and described.

DESCRIPTION

FIG. 1 is a top, front and right-side perspective view of a faucet showing our new design;

FIG. 2 is a bottom, rear and left-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of the portion 9 in FIG. 1; and, FIG. 10 is a perspective view of the faucet shown in a state of use.

The broken lines shown in FIGS. 1-3 and 5-9 depict portions of the faucet and form no part of the claimed design. The dot-dot-dash lines in FIGS. 1 and 9 denote the boundary of the enlarged view and form no part of the claimed design. The broken lines in FIG. 10 represent portions of the faucet and environment structure and form no part of the claimed design. The dot-dot-dash line in FIG. 10 is for the purpose of illustrating a view with environment and forms no part of the claimed design.
